UNITED STATES PATENT OFFICE.

GUSTAVO TRIFARI, OF NEW YORK, N. Y., ASSIGNOR TO TRIFARI, KRUSSMAN & FISHEL, INC., OF NEW YORK, N. Y.

DESIGN FOR A HAIRBRUSH.

Application filed October 6, 1926. Serial No. 19,255. Term of patent 3½ years.

To all whom it may concern:

Be it known that I, GUSTAVO TRIFARI, a citizen of the United States, residing in the city of New York, county of New York, and State of New York, have invented a new, original, and ornamental Design for a Hairbrush, of which the following is a specification, reference being had to the accompanying drawing, forming part thereof.

I claim:

The ornamental design for a hairbrush, as shown.

GUSTAVO TRIFARI.
